[57] CLAIM

The ornamental design for a float for eyeglasses, as
shown and described.

DESCRIPTION

FIG. 1 is a perspective view of a float for eyeglasses showing my new design, the broken line showing of the
spectacles is for illustrative purposes only and forms no
part of the claimed design;

FIG. 2 is a front elevational view thereof;

FIG. 3 is a rear elevational view thereof;

FIG. 4 is a side elevational view thereof, the side oppo-
site being identical; and,

FIG. 5 is an end elevational view thereof, the end oppo-
site being identical.

FIG.-1

FIG.-2FIG.-3FIG.-4FIG.-5
